US00D767567S

(12) **United States Design Patent** (10) **Patent No.:** **US D767,567 S**
(45) **Date of Patent:** **** Sep. 27, 2016**

(54) **WIRELESS INPUT DEVICE WITH BAND**

(71) Applicant: **Amazon Technologies, Inc.**, Seattle, WA (US)

(72) Inventor: **Giles David Matthew McWilliam**, San Francisco, CA (US)

(73) Assignee: **Amazon Technologies, Inc.**, Seattle, WA (US)

(**) Term: **14 Years**

(21) Appl. No.: **29/520,233**

(22) Filed: **Mar. 12, 2015**

(51) **LOC (10) Cl.** **14-02**

(52) **U.S. Cl.**

USPC **D14/358**

(58) **Field of Classification Search**

USPC D14/300, 314, 217, 218, 348, 349, 353, D14/355, 356, 357, 358, 363-370, 383, 388, D14/432, 439, 299, 902, 480.2, 480.3, D14/480.5, 480.6, 188; D13/123, 133, 162, D13/162.1, 168, 173, 184, 199; D18/4.4; D20/99, 1, 8; D10/104.1
CPC .. G06K 19/0723; H04W 4/00; H04W 4/206; H04W 4/021; H04W 4/0241; H04W 4/005; H04W 4/22

(57) **CLAIM**

The ornamental design for a wireless input device with band, as shown and described.

DESCRIPTION

FIG. 1 is a first perspective view of a wireless input device with band, taken from above;

FIG. 2 is a second perspective view of the wireless input device with band, taken from below;

FIG. 3 is a front view of the wireless input device with band of FIG. 1;

FIG. 4 is a back view of the wireless input device with band of FIG. 1;

FIG. 5 is a right-side view of the wireless input device with band of FIG. 1;

FIG. 6 is a left-side view of the wireless input device with band of FIG. 1;

FIG. 7 is a top plan view of the wireless input device with band of FIG. 1; and,

FIG. 8 is a bottom plan view of the wireless input device with band of FIG. 1.

The broken lines in the drawings depict portions of the wireless input device with band that form no part of the claim.

1 Claim, 6 Drawing Sheets
